CAMERA TRIPOD DOLLY

Robert W. Bradspies, Pasadena, and Edwin V. Stephens, Los Alamitos, Calif., assignors to CinTel Corporation, Los Angeles, Calif.

Filed June 16, 1970, Ser. No. 23,513

Term of patent 14 years

Int. Cl. D12—02

U.S. Cl. D14—3

FIG. 1 is a perspective view of a camera tripod dolly showing our new design; and

FIG. 2 is a side elevational view, the opposite side being a mirror image thereof; and

FIG. 3 is a top plan view of FIG. 2; and

FIG. 4 is a bottom plan view of FIG. 2; and

FIG. 5 is a top plan view of FIG. 3 with the legs in a folded position.

We claim:

The ornamental design of a camera tripod dolly, substantially as shown and described.
